SAFETY DEVICE FOR POLISH ROD MOUNTINGS OF DEEP WELL PUMPS

George E. Owen, Downey, and Harris L. Brendt,
Long Beach, Calif.

Application May 24, 1948, Serial No. 28,886

7 Claims. (Cl. 192—116.5)

1

This invention relates to safety controls, and more particularly to safety control devices especially adapted for use in connection with deep well pumps.

An important object of the invention is to provide safety means which will cut off the power employed in pumping deep wells in the event that the sucker rods which operate the pump should break or in the event that cable lengths from which the sucker rods are suspended should become unduly weakened or break.

As is well understood, deep wells of the oil well type are pumped by the reciprocation of long pump rods, commonly known as sucker rods, which depend in the pump tubing and carry at their lower ends pistons reciprocating in the pump barrels at the bottoms of the wells. The upper ends of these sucker rods are commonly suspended from cross heads or carrier bars which are in turn supported on the lower ends of short cable lengths and actuated by the common walking beams which are rocked upon appropriate mountings by devices which commonly are internal combustion engines or electric motors. Frequently, the sucker rods part, and on occasion the suspending cables fray or break. Under such circumstances the power mechanism and the walking beam of such a well tend to run wild and frequently produce serious damage.

It is, therefore, a general object of this invention to provide safety means which will prevent the power mechanism from running wild and will avoid all damage incident to the development of such condition.

Another object is to produce a safety mechanism which is positive, efficient, relatively inexpensive to manufacture, and very easy to install.

Other objects and various features of the invention will become apparent to those skilled in this art upon reference to the following specification and accompanying drawing wherein one embodiment of the invention is illustrated.

In the drawing:

Fig. 1 is a side elevation illustrating the equipment employed commonly at the top of a pumping well, the invention hereof being illustrated in operative relationship with respect to such mechanism;

Fig. 2 is an elevational view showing a structure as seen from the right of Fig. 1;

Fig. 3 is principally a large scale top plan view of the structure of this invention, as indicated by the line 3—3 of Fig. 2, associated parts being

2

shown in cross section, and portions being broken away to facilitate disclosure;

Fig. 4 is a fragmentary end view on an enlarged scale as indicated by the line 4—4 of Fig. 3;

Fig. 5 is a front elevation of the structure of Fig. 3, being shown on the same enlarged scale as in Fig. 3;

Fig. 6 is a fragmentary detail showing a desirable structural feature omitted from Fig. 3 to facilitate the disclosure; and

Fig. 7 is a perspective view on a reduced scale, a possible variation being shown.

Having reference to Fig. 1 of the drawing, 15 a conventional walking beam 10 is shown as being mounted through the medium of a pivot shaft 11 upon the upper end of a support 12 of conventional construction. The walking beam 10 is conventionally rocked by the usual pitman 14 pivotally connected with the outer end of a rotating arm 15 actuated through mechanism in a gear case 16 from an engine 17 or similar prime mover. A conventional counterbalance 18 connected with the arm 15 is also illustrated.

The opposite end of the walking beam 10 is shown as being equipped with a usual arcuate structure 20, commonly known as a horsehead, presenting an outer, curved working surface upon which two short supporting cables 22 bear, their upper ends being commonly integrally joined and mounted on the upper end of the curved surface of the horsehead 20 as by fixing to a saddle 23. The walking beam 10, through the horsehead 20 and the short cables 22, serves to reciprocate the usual "polish rod" 24 which is the top joint of the usual sucker rod assembly of a deep well pump 25, this reciprocation being effected through the medium of a cross head 26 commonly known in the oil industry as a carrier bar

30 and carrying a clamp 27 of any preferred form bound to the polish rod 24. The lower ends of the cables 22 are fixed in the outer ends of the cross heads 26 as indicated at 28.

The safety device of this invention is generally indicated at 30 and is principally shown in Figs. 3 and 5. Its purpose is to cut off power to the engine 17 in the event that the sucker rod should break or part at any point, or the cables 22 pull loose from their mountings at 23 or 28, or break, or become unduly weakened by fraying or otherwise. The safety device 30 operates to retain a control device 31 under normal operating conditions and to release the control device 31 in the event of the breaking or weakening just indicated. The control device 31 is carried on the end

of a line 32 which leads to an appropriate junction box 33 or the like from which an electric conduit 34 leads to a magneto on the engine 17. According to one form, the control device 31 may be a mercury switch which is open when the device 31 is in the upright position seen in Fig. 1, and is closed to ground the magneto if the control device 31 is dropped and becomes inverted. Or, the control device 31 might be a weight which when dropped will act through the line 32 to 10 jerk a switch mechanism in the junction box 33 and open the circuit if an electric motor replaces the engine 17.

Referring especially to Fig. 3, the safety device 30 comprises, as its principal constituents in the form shown, two opposing arms 35 clamped to the cables 22, two aligned, oppositely operating, expansible coil springs 36 adapted to be connected to the polish rod 24 at their inner ends and having bearing heads 38 at their outer ends, bearing seats 40 secured at the outer ends of the arms 35 and receiving the bearing heads 38, and a latch mechanism 41 adapted to carry the control device 31 and attached to the ends of the arms 35 adjacent the seats 40.

The seats 40 are of any appropriate cupped or similar formation, such as the trough-like members shown which are provided at their bottoms with stops 40a (Fig. 5) to limit downward movement of the heads 38. As illustrated, the latch mechanism 41 comprises a pin 42 attached to an adjacent end of a linkage 43, such as a chain section 43a, the other end of the linkage 43 being attached to the outer end of one of the arms 35 as presently to be described. Another part of the latch mechanism 41 as illustrated is in the form of a cylindrical block 44 which receives the pin 42 in a bore disposed at its axis. The block 44 is carried on an adjacent end of a bracket 45 attached to the outer end of the other arm 35 through the medium of an upstanding leg 45a.

Each arm 35 is clamped to its respective cable 22 by any appropriate means, that shown comprising a U-shape block 46 providing spaced jaws between which the cable is received as shown and a U-bolt 47 of conventional construction extending through appropriate passages in the U-shape block 46 and through openings in the respective arm 35, the ends of the U-bolt 47 receiving anchor nuts 48 which bind the block to the cable 22 and thereby secure the respective end of the arm 35 to its cable 22. The outer end of each arm 35 is provided with an appropriate ear 50 mounted upon a flange 51 preferably integral with the respective end of the respective arm 35. One of the ears 50 receives the upper end of the upstanding leg 45a which is appropriately secured in place in any preferred manner, as by a set screw 52 and upper and lower nuts 53 which may be bound against the under and upper sides of the respective ear 50. Such means serve to anchor the bracket 45 in any vertically and horizontally adjusted position such as that illustrated. The free end of the bracket 45 carries the cylindrical block 44 through the medium of such means as a screw 54. It will be noted that the cylindrical block 44 is provided with an overhanging extension 44a spaced from the body of the block 44 by a slot 55 which is directed downward, as indicated in Fig. 5, when the parts are in their operative relationship as seen in Fig. 3. The slot 55 is adapted to receive an eye 56 carried upon the upper end of the control device 31, such eye

56 being supported upon the inner end of the pin 42 when in the operative relationship indicated in Fig. 3. When the pin 42 is in such operative position its eye-supporting extremity bears against the inner face of the overhanging extension 44a, being received in a countersunk seat therefor, if preferred. Desirably, the pin 42 is positively retained in such operative position as by means of a U-spring 57 (Fig. 4) engaging in appropriate notches or in a peripheral groove in the pin 42, the spring 57 being mounted in the outer end of the cylindrical block 44 as by means of a screw 58.

The end of the linkage 43 opposite from the latch mechanism 41 is attached to the outer end of the respective arm 35 through the medium of a depending shank 60 whose upper end is secured to the respective ear 50 as by means of nuts 61 and whose lower end is secured as by means of nuts 62 to an adjacent end of a rigid link 63 connected by a turn buckle 64 to a threaded link 65 or the like fixed to the adjacent end of the chain section 43a.

The inner or opposing ends of the expansible coil springs 36 are provided with mounting means so that they may be properly positioned by being mounted upon the upper end of the polish rod 24. Such mounting means may be in the form of a clamp 70, as indicated in Fig. 3 and in Fig. 5, or by means of a yielding retainer 72 as indicated in Fig. 7. The clamp of Fig. 3 is shown as being formed of two conventional clamp parts 74 held on the sucker rod 24 by bolts 75. Each part 74 has fixedly secured thereto a screw threaded shank 76 which extends into the respective spring 36 and carries a retaining and tensioning nut 77 bearing against the adjacent spring end and cooperating with a lock nut 78. Thus, proper tension is readily placed upon the spring 36 by the nut 77 and retained by the lock nut 78. With the mounting shown in Fig. 3, it is desirable that the outer ends of the springs 36 be welded to the bearing heads 38 as indicated at 79, but a preferable construction may be that shown in Fig. 6 where a sleeve 80 is disposed between each spring 36 and its threaded shank 76. In this form, each bearing head 38 may be provided with a stud 82 over which the respective end of the sleeve 80 fits, or the corresponding end otherwise secured to the bearing head as preferred. The sleeves 80 thus properly guide the outer ends of their springs 36.

As to the retainer 72 shown in Fig. 7, which is adapted to be employed instead of the clamp 70 of Figs. 3 and 5, the two threaded shanks 76 carrying the springs 36 are respectively attached to two spaced bars 85 which in turn carry opposed jaws 86 which are generally semi-cylindrical to engage around the polish rod 24 and are retained in such position by contracting coil springs 88 attached to the opposed ends of the bars 85. Thus, the curved jaws 86 are frictionally held by the springs 88 in engagement with the walls of the polish rod 24. Preferably, the upper ends of the jaws 86 are tapered outward as illustrated so that, should the clamp 70 on the cross head 26 fail to hold the polish rod 24, any type of stop shoulder 90 carried at the upper end of the polish rod may pass therethrough without damaging the safety device 30. Such collar or shoulder 90 may, of course, then be caught upon any safety retainer carried by the cross head 26 or upon the top of the well pump, or elsewhere as preferred.

Operation

As will be apparent from the foregoing description, when the weight of the sucker rods and the pump parts suspended thereby in the bottom of the well is imposed upon the cables 22 by being secured to the cross head 26 through the medium of the clamp 27, such cables 22 are placed under a heavy strain tending to maintain them against any flexure. The arms 35 are then secured upon the cables 22 through the medium of the clamps 46, 47 and the clamp 70, or the retainer 72, is positioned upon the upper portion of the sucker rod 24, and the expandable coil springs 36 are directed so that the bearing heads 38 are positioned in the bearing seats 40 on the outer ends of the arms 35. The tensioning nuts 71 are then turned down against the inner ends of the respective springs 36 so as to place sufficient tension thereon to cause the arms 35 to be forced apart should any large proportion of the weight on the sucker rods be released as by breakage, or should a sufficient number of strands of either of the cables 22 break to render the respective cable dangerous and thereby enable it to be twisted by reason of the pressure exerted by the springs 36.

The turnbuckle 64 is then adjusted so that substantially all slack is taken from the chain section 43a when the pin 42 is inserted into the bore of the cylindrical block 44 of the latch mechanism 41. The eye 56 upon the upper end of the control device 31 is then introduced into the vertically disposed slot 55 in the cylinder block 44, and the pin 42 is passed through the eye 56 and into the operative position indicated in Fig. 3. The U-spring 57 on the outer end of the block 44 serves to retain the pin 42 positively in such operative position. Under these conditions the control device 31 is suspended as seen in Fig. 1.

The line 32 which connects the control device 31 with the junction box 33 on the walking beam support 12 is sufficiently long to provide for the usual reciprocating movement of the cross head 26 as it is actuated by the horsehead 20. Should enough of the strands of one of the cables 22 become broken to dangerously weaken the cable, such weakening will enable the tension in the springs 36 to twist that cable 22 by forcing the outer end of the respective arm 35 outward away from the polish rod 24 and the other arm 35. This movement may be aided by a natural untwisting tendency of the cable when some of the strands break.

When such movement becomes sufficient to be a measure of a dangerous situation, the pin 42 is pulled from the slot 55 and the control device 31 drops by reason of release of the eye 56 on its upper end. If the device 31 contains a mercury switch, the circuit to the magneto of the engine 17 is grounded by reason of the closing of said switch, or, if the device 31 is a weight and an electric motor is used, the circuit is broken by reason of the actuation of a switch in the junction box 33 under influence of the weight. Thus, the engine or motor is stopped and operation of the walking beam 10 ceases. Should the sucker rod or the polish rod 24 break, a similar result takes place because of the fact that removal of the load from the cables 22 permits the arms 35 to be forced apart by the springs 36 thereby dislodging the pin 42 from its position in the cylindrical block 44.

It is, therefore, apparent that the safety device herein disclosed readily adapts itself to installation on a pump reciprocating mechanism

of the described character and will automatically function to stop the motor upon failure to a predetermined degree of the sucker rod or its supporting means. Since it is mounted at the most sensitive point, the engine or motor is shut off instantly upon any failure, and without any speed-up to actuate the device or running out of control. Also, the device performs shock absorbing functions upon the cables to minimize ordinary twisting and give them longer life.

Variations of the generic invention herein disclosed are intended to be protected insofar as they fall within the scope of the claims.

We claim as our invention:

- 15 1. In a safety combination: a weighted device; spaced, twisted strand cables supporting said weighted device; plural cable engaging means respectively secured to said cables; arm means extending respectively from said cable engaging means in spaced relation; plural tension means mounted on said weighted device, and respectively engaging extending portions of the respective arm means, and maintained in normal tension by weight stresses on said cables when the cables are in normal condition and acting to twist said cables into distorted condition under other conditions, said tension means being opposing spring means having mountings positioning them on said weighted device and on said extending portions of said arm means, said spring means serving to produce relative distortion of said cables in the event of breakage of strands of said cables; relatively movable controlling means operatively connected with said arm means and tension means for actuation upon relative cable distortion; and a control device carried by said relatively movable controlling means for control of a power mechanism operating said weighted device, said control device being energizable through movement of said relatively movable controlling means upon development of said relative cable distortion.
- 20 2. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 25 3. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 30 4. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 35 5. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 40 6. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 45 7. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 50 8. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 55 9. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 60 10. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 65 11. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 70 12. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to
- 75 13. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to

the other clamped to the other of said cables and both disposed in a plane to which the polish rod is perpendicular; an expansible assembly having one end seated on the free end of one of said arms and its other end seated on the free end of the other of said arms, said expansible assembly having expansion spring means so placed as to tend to force said ends of said expansible assembly apart and thus rotate each of said arms about its cable and force the free ends of said arms apart; a latch mechanism comprising a primary connecting member having a first end attached to the free end of one of said arms, a secondary connecting member having a first end attached to the free end of the other of said arms, and a connecting assembly detachably connecting the second ends of said primary member to the second end of said secondary member in such a manner that said second ends are disconnected when the free ends of said arms are moved apart; and means by which the disconnection of said second ends stops the prime mover.

4. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to which the polish rod is perpendicular; an expansible assembly having one end seated on the free end of one of said arms and its other end seated on the free end of the other of said arms, said expansible assembly having expansion springs so placed as to tend to force said ends of said expansible assembly apart and thus rotate each of said arms about its cable and force the free ends of said arms apart; a latch mechanism comprising a primary connecting member having a first end attached to the free end of one of said arms, a secondary connecting member having a first end attached to the free end of the other of said arms, and a connecting assembly detachably connecting the second ends of said primary member to the second end of said secondary member in such a manner that said second ends are disconnected when the free ends of said arms are moved apart; a flexible member having a first end attached to a stationary part of the derrick in which the above parts are located and a second end carried to said connecting assembly and detachable therefrom whenever the second ends of said connecting members are disconnected; and means by which the disconnection of said flexible member stops the prime mover.

5. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to which the polish rod is perpendicular; an expansible assembly having one end seated on the free end of one of said arms and its other end seated on the free end

of the other of said arms, said expansible assembly having expansion springs so placed as to tend to force said ends of said expansible assembly apart and thus rotate each of said arms about its cable and force the free ends of said arms apart; means by which the center of said expansible assembly is rigidly connected to the upper end of the polish rod; and means by which the separation of the free ends of said arms stops the operation of the prime mover.

6. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being reciprocated between limits by a prime mover, comprising in combination with said above enumerated parts: two arms, one clamped to one of said cables and the other clamped to the other of said cables and both disposed in a plane to which the polish rod is perpendicular; an expansible assembly having one end seated on the free end of one of said arms and its other end seated on the free end of the other of said arms, said expansible assembly having expansion springs so placed as to tend to force said ends of said expansible assembly apart and thus rotate each of said arms about its cable and force the free ends of said arms apart; means by which the center of said expansible assembly is rigidly connected to the upper end of the polish rod; a latch mechanism comprising a primary connecting member having a first end attached to the free end of one of said arms, a secondary connecting member having a first end attached to the free end of the other of said arms, and a connecting assembly detachably connecting the second ends of said primary member to the second end of said secondary member in such a manner that said second ends are disconnected when the free ends of said arms are moved apart; and means by which the disconnection of said second ends stops the prime mover.

7. A safety device for use in oil wells in which a polish rod is attached at its lower end to a string of sucker rods extending downwardly into the well and actuating a pump and attached at its upper end to a cross head which is suspended from a walking beam by two sucker rod supporting cables, the walking beam being carried upon a support and reciprocated between limits by a prime mover, comprising in combination with said above enumerated parts: two arms, one clamped to one of said cables and the other clamped to the other of said cables and both disposed in a plane to which the polish rod is perpendicular; an expansible assembly having one end seated on the free end of one of said arms and its other end seated on the free end of the other of said arms, said expansible assembly having expansion spring means so placed as to tend to force said ends of said expansible assembly apart and thus rotate each of said arms about its cable and force the free ends of said arms apart; means by which the center of said expansible assembly is rigidly connected to the upper end of the polish rod; a latch mechanism comprising a primary connecting member having a first end attached to the free end of one of said arms, a secondary connecting member having a first end attached to the free end of the other of said arms, and a connecting assembly detachably connecting the second ends of said primary member to the second end of said sec-

ondary member in such a manner that said second ends are disconnected when the free ends of said arms are moved apart; a flexible member having a first end attached to a stationary part of said support and a second end carried to said connecting assembly and detachable therefrom whenever the second ends of said connecting members are disconnected; and means by which the disconnection of said flexible member stops the prime mover.
